(57) **CLAIM**

The ornamental design for a phone cover with integral card holder, as shown and described.

DESCRIPTION

FIG. 1 is a front perspective view of a phone cover with integral card holder according to our new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof; and,

FIG. 7 is a bottom plan view thereof.

In FIG. 1, the broken lines and the unshaded region on the front of the case depict an unclaimed cell phone. In FIG. 6, the broken lines and the unshaded regions that are bounded by broken lines depict unclaimed cards.

UNITED STATES PATENT AND TRADEMARK OFFICE
Certificate

Patent No. D. 653,656 S

Patented: February 7, 2012

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Brandon Charnas, East Hills, NY. (US)

Signed and Sealed this Fifth Day of March 2013.

ROBERT SPEAR
Supervisory Patent Examiner
